[57] CLAIM

The ornamental design for a combined protector and disposer, as shown and described.

DESCRIPTION

FIG. 1 is a top/front/right side perspective view of a combined needle protector and disposer showing our new design;

FIG. 2 is a top plan view thereof;

FIG. 3 is a bottom plan view thereof; and,

FIG. 4 is a front elevational view thereof, all other elevational views being identical thereto.

FIG. 1

FIG. 4

FIG. 2

FIG. 3
